Attorney

UNITED STATES PATENT OFFICE.

EDWARD TOBIAS, OF PRESCOTT, WISCONSIN.

HAYRACK.

Application filed March 3, 1924. Serial No. 696,558.

To all whom it may concern:

Be it known that I, EDWARD TOBIAS, a citizen of the United States, residing at Prescott, in the county of Pierce and State of Wisconsin, have invented certain new and useful Improvements in Hayracks, of which the following is a specification.

This invention relates to hay racks and it consists in the novel features hereinafter described and claimed.

An object of the invention is to provide a hay rack structure including a frame mounted upon converging beams adapted to lie transversely of the front and rear bolsters of the running gear of the wagon. At the rear bolster, the beams fit snugly between the stakes and at the front bolster, the beams are spaced from the stakes thereby providing ample clearance space for the forward wheels to swing without coming in contact with the said beams.

In the accompanying drawings:—

Figure 1 is a top plan view of the hay rack.

Figure 2 is an enlarged perspective view of the spacing means used upon the beams of the rack.

As illustrated in the accompanying drawing, the rear bolster of the wagon running gear is indicated at 1 and the front bolster at 2. These bolsters are provided at their end portions with the usual upstanding stakes 3. The rack comprises beams 4 which are disposed transversely across the intermediate portions of the bolsters 1 and 2. The beams 4 converge toward each other from their rear ends toward their forward ends. A frame 5 is mounted upon the beams 4. At their rear portions, the beams 4 fit snugly between the stakes 3 which are carried by the rear bolster 1 and at their forward

end portions, the beams 4 are spaced from the stakes 3 which are carried upon the bolster 2. Spacing members 6 are mounted upon the outer surfaces of the forward portions of the beams 4 and are adapted to receive the inner portions of the stakes 3 which are carried by the bolster 2. Each spacing member includes a pair of plates 7 having intermediate parallel portions riveted together as at 8, and angularly disposed flange portions 9 which are secured to the beams 4. The plates are provided at their outer ends with clip or socket portions 10 adapted to receive the inner portions of the stakes 3 which are carried by the bolster 2.

By such an arrangement, it is obvious that ample space is provided between the beams 4 and the forward wheels of the running gear of the wagon to permit the said wheels to turn without coming in contact with the beams 4. Thus the hay rack may be used upon a wagon running gear, and the running gear may make comparatively short turns.

Having described the invention, what is claimed is:

In a hay rack, a spacing member adapted for disposition between a stake and a sill, said member comprising a pair of duplicate plates having their intermediate portions secured together, corresponding ends of said plates being bent laterally in opposite directions to provide attaching flanges, the opposite ends of the plates being bent laterally in opposite directions and then outwardly in spaced parallelism to provide a socket for reception of the stake, the extremities of the last named ends of the plates being flared to facilitate a connection with the stake.

In testimony whereof I affix my signature.

EDWARD TOBIAS.
